Patented Nov. 26, 1918.

UNITED STATES PATENT OFFICE.

AQUILA S. ROBINSON, OF PHILADELPHIA, PENNSYLVANIA, ASSIGNOR TO METROPOLITAN SEWING MACHINE CORPORATION, A CORPORATION OF DELAWARE.

CUTTING-OFF ATTACHMENT FOR SEWING-MACHINES.

1,286,113.

Specification of Letters Patent. Patented Nov. 26, 1918.

Application filed December 18, 1917. Serial No. 207,765.

To all whom it may concern:

Be it known that I, AQUILA S. ROBINSON, a citizen of the United States, residing at Philadelphia, in the county of Philadelphia, 5 and State of Pennsylvania, have invented certain new and useful Improvements in Cutting-Off Attachments for Sewing-Machines, of which the following is a specification.

This invention relates to cutting attachments for sewing machines, the object of the invention being to provide a simple and effective cutting attachment that can readily be applied to the work or cloth plate of any sewing machine, so that as the work is 15 stitched by the machine it may be cut in any desired lengths by a simple manipulation of a foot treadle or knee shift.

Another object of the invention is the provision of an improved cutting attachment, 20 so located on the work or cloth plate of a sewing machine in the rear of the stitching and feeding mechanism, that it may be readily adjusted relative to the line of feed and also at right angles to the line of feed, 25 so that the depth of the cut effected by the cutting members can be regulated whereby certain portions of the goods may be cut or notched without the necessity of cutting other portions thereof, so that the cutting attachment may be used either to cut a gash 30 or notch in the edge of the goods being stitched or used to cut off strips as they are stitched.

Heretofore it has been the usual custom to 35 run a number of connected garments,—say a dozen,—one after another, letting them pile up in the rear of the machine, which more or less retarded the handling and feeding of the work, and after the completion of 40 a dozen garments the operator would separate them by the use of scissors or shears.

The object of the present improvement however, is to provide a very simple and efficient cutting attachment which will separate the articles as they are stitched by the 45 sewing machine, and is particularly useful where continuous top or top and bottom strips are applied to the edge of a garment, such as button stays, button hole facing, 50 drawer bands, etc., wherein as each garment is passed into the machine to be stitched, and as the stitching operation is completed, the cutters may be actuated by the movement of the foot or knee of the operator, and so 55 severed from the strips, whereby the several

garments may be separated so that each garment may be removed from the rear of the machine as it is finished.

In the drawings accompanying and forming 60 a part of this specification,

Figure 1 is a top view of this improved cutting attachment applied to the work plate of a sewing machine, only so much of the presser foot and stitching mechanism as is deemed necessary to clearly illustrate the invention being shown; Fig. 2 is a view of the attachment looking in the direction of the arrow, Fig. 1; Fig. 3 is an end view of the attachment looking in the direction of the arrow A in Fig. 1; Fig. 4 65 is a sectional view of the bottom knife or cutter taken on the line 4—4 of Fig. 3; Fig. 5 is a sectional view of the swinging knife taken on the line 5—5, Fig. 3; and Fig. 6 is a perspective detail view of the segmental 70 gear teeth carried by the swinging knife and by the shaft for operating said knife.

Similar characters of reference indicate 75 corresponding parts in the several figures of the drawings.

In the preferred form thereof herein shown, the work plate 1, the presser foot 2, the needle holes 3 through which the needles pass to effect the stitching illustrated at 4, may be of the usual construction so that a 80 detail description thereof is deemed unnecessary. A facing strip 5 and a lining strip 6 are shown passing under the presser foot, and serve to illustrate how these strips of fabric pass through the stitching mechanism to the cutting mechanism about to be 85 described.

This improved cutting attachment comprises a bracket 7, provided with two elongated slots 8 through which attaching screws 9, having lock nuts and washers 9' and 9'', pass to secure the bracket to the work plate, and the work plate 1 is also provided with elongated slots 10 extending at right angles to the slots 9, thus providing means for adjusting the bracket 7 in either direction, that is, to and from the line of feed and also at right angles thereto in a manner which will be readily understood. This bracket 7 is provided with two upright bearings 11 95 spaced apart and in these bearings is located a rock shaft 12, to one end of which is secured by means of a pin 14 a lever 15, which lever is connected by a rod 16 with a floor treadle 17 or its equivalent, such as a knee 100 105

shift. The lever is also drilled as at 18 to 21 in directions transverse to each other to receive one end of a coiled spring 19, the ward and from the stitching mechanism, cutting opposite end 20 of which extends into a hole 21 in the rear bearing 11. This spring 19, acting at an angle to the line of feed, and normally tends to keep the cutting knives means for operating said cutting means open. 76

The other front end of the shaft 12 is chimes comprising a bracket adjustably attached to the work plate of a sewing machine 22, whereby the bracket may be adjusted in direction of a similarly formed opening 22, carried by a segmental gear 23, which gear is directions transverse to each other toward 78 and, the construction is such that endwise means carried by the bracket and operating end moving of the shaft in its bearings is prevented an angle to the line of feed, and means 24. This segmental gear 23 co-operates for operating said cutting means, said cutting 25 with similarly formed gear 25 carried at the cutting means comprising a fixed knife and a 80 rear end of the pivoted or swinging cutting knife, said swinging knife having a blade 27. This blade is concaved in segmental gear teeth and said operating end along its side face as at 28 (see Fig. 5) and means having corresponding gear teeth 29 is provided, with a cutting edge 29 and a 30. A cutting attachment for sewing ma- 82 hical portion 30. The blade is pivotally se-chimes comprising a bracket adjustably at- 84 ched in frictional contact with the face of attached to the work plate of a sewing ma- 86 chine 31 carried by the bracket 7, by a screw 31 and spring washer 32, the screw 31 in directions transverse to each other toward 88 passing through a hole 26 in the blade located and from the stitching mechanism, cutting 27 at the rear of the cutting portion of the means carried by the bracket and operating 90 blade. The opposite end of this screw 31 is at an angle to the line of feed, means for 92 provided with a lock nut 34, which together operating said cutting means, said cutting 94 with the spring washer is effective to regu- means comprising a fixed knife and a swing- 96 lating the tension which may be imparted to said knife, said swinging knife having seg- 98 ments 35 to receive the bottom or stationary, having corresponding gear teeth, and means 100 for maintaining the cutting knife away from 102 by screws 37. This fixed knife has a thin fixed knife, maintained 104 (see Fig. 4) located in the line of feed. A cutting attachment for sewing ma- 106 chine comprising a bracket adjustably at- 108 mechanism, so that the work will readily attached to the work plate of a sewing machine 110 passing over this thin edge of the knife and whereby the bracket may be adjusted in di- 112 rectly over the cutting edge 39 of such knife. A 114 sections transverse to each other toward and 116 segmental gear 40 is provided on the opposite from the stitching mechanism, cutting means 118 edge of the knife to properly co-operate with carried by the bracket and operating at an 120 122 cutting edge 29 of the swinging knife 27, an angle to the line of feed, means for oper- 124 ating. To properly protect the operator and the cutting said cutting means, said cutting means 126 from the segmental gears, a pair of walls 41 and 42 are vertically extending, said knife, said swinging knife having segmental 128 gear teeth 43 carried by the bracket 7 and so located as to gear teeth and said operating means having 130 forming a slot or recess 43 therebetween, in corresponding gear teeth, and means for 132 which recess and between which walls the maintaining the cutting knife away from the 134 segmental gear teeth are located as well as fixed knife, said fixed knife having a thin 136 rear portion of the swinging cutting front edge and a raised cutting edge. 138

50 A cutting attachment for a sewing ma- 140 chine. From the foregoing, it will be observed chine located to operate at an angle to the 142 that the present improvement provides a line of feed and comprising a fixed knife, 144 positively acting simple and efficient cutting a swinging knife formed with segmental 146 attachment easily and quickly manipulated gear teeth, and means for operating it and 148 by the operator, and which may be readily also having segmental gear teeth meshing 150 with the teeth of the swinging knife. 152 A cutting attachment for a sewing ma- 154 chine from the stitching mechanism, whereby the chine located to operate at an angle to the 156 entire work may be severed or only a portion chine located to operate at an angle to the 158 thereof cut or notched as the stitching opera- line of feed and comprising a fixed knife, a 160 tion proceeds. It is believed a cutter of 162 swinging knife formed with segmental gear 164 teeth, means for operating it and also having 166 segmental gear teeth meshing with the 168 teeth of the swinging knife, and means for 170 maintaining the swinging knife spaced from 172 the fixed knife, all to said to foot sit to 174 176 said a as does the wings of the 178 180 182 184 186 188 190 192 194 196 198 200 202 7. A cutting attachment for a sewing machine located to operate at an angle to the line of feed and comprising a bracket, a rock shaft carried thereby, a segmental gear carried by said shaft, means for operating said shaft, a fixed knife, and a swinging knife pivotally secured to said bracket and formed with segmental gear teeth meshing with the segmental gear carried by the rock shaft.

8. A cutting attachment for a sewing machine located to operate at an angle to the line of feed and comprising a bracket, a rock shaft carried thereby, a segmental gear carried by said shaft, means for operating said shaft, a fixed knife, a swinging knife pivotally secured to said bracket and also having segmental gear teeth meshing with the segmental gear carried by the rock shaft, and a spring carried by said shaft for maintaining the swinging knife away from the fixed knife.

9. A cutting attachment for a sewing machine located to operate at an angle to the line of feed and comprising a bracket, a rock shaft carried thereby, a segmental gear carried by said shaft, means for operating said shaft, a fixed knife, and a swinging knife pivotally secured to said bracket and formed with segmental gear teeth meshing with the segmental gear carried by the rock shaft, said fixed knife having a thin front edge and a raised cutting edge and said swinging knife having a concaved front side and an inclined rear side.

10. A cutting attachment for a sewing machine comprising a bracket, a rock shaft carried thereby, means for rocking said shaft, a segmental gear carried at the opposite end of said shaft, a fixed knife carried by said bracket and projecting forwardly thereof transversely of the line of feed of the sewing machine, a swinging knife pivotally secured to said bracket and also having segmental gear teeth meshing with the segmental gear, said bracket having a pair of upstanding walls forming a recess between which said segmental gear teeth and the rear end of the swinging knife are located.

11. A cutting attachment for a sewing machine comprising an adjustable bracket adjustable in different directions, a rock shaft carried by said bracket, means at one end thereof for rocking said shaft, a pair of upstanding walls carried by said bracket, a segmental gear at the opposite end of said rock shaft and located between said walls, a

fixed knife carried by the bracket and extending across the line of feed of the work, a swinging knife pivotally secured to the bracket and having at its rear end segmental gear teeth coöperating with the segmental gear and also located between said upstanding walls, a fixed knife having a thin front edge and a raised rear cutting edge with a relief portion adjacent thereto, the swinging knife having a concaved front side and an inclined rear side, and a spring carried by said rock shaft for maintaining the swinging knife away from the fixed knife.

12. A cutting attachment for sewing machines comprising a fixed knife extending across the line of feed of the work, a swinging knife coöperating therewith, means including gearing for operating said swinging knife, and upstanding walls inclosing said gearing and protecting the work therefrom.

13. A cutting attachment for sewing machines located at an angle to the line of feed and comprising a bracket having a pair of upstanding protecting walls forming a recess therebetween, a fixed knife and a swinging knife, the latter pivotally secured to said bracket, and means for operating said swinging knife and comprising gearing located between said upstanding walls.

14. A cutting attachment for sewing machines located at an angle to the line of feed and comprising a bracket having a pair of upstanding protecting walls forming a recess therebetween, a fixed knife and a swinging knife, the latter pivotally secured to said bracket, means for operating said swinging knife and comprising gearing located between said upstanding walls, and means for maintaining the swinging knife away from the fixed knife.

15. A cutting attachment for sewing machines located at an angle to the line of feed and comprising a bracket having a pair of upstanding protecting walls forming a recess therebetween, a fixed knife and a swinging knife, the latter pivotally secured to said bracket, means for operating said swinging knife and comprising a gearing located between said upstanding walls, means for maintaining the swinging knife away from the fixed knife, and means for adjusting the bracket in directions transverse to each other toward and from the work.

Signed at Philadelphia, Pennsylvania, this 11th day of December, 1917.

AQUILA S. ROBINSON.
